(57) **CLAIM**

We claim the ornamental design for a bracelet, as shown and described.

DESCRIPTION

FIG. 1 is a perspective view of an embodiment of the bracelet.

FIG. 2 is a front view thereof.

FIG. 3 is a rear view thereof.

FIG. 4 is a side view thereof.

FIG. 5 is a side view thereof.

FIG. 6 is a top view thereof.

FIG. 7 is a bottom view thereof.

FIG. 8 is an exploded view thereof.

FIG. 9 is a perspective view of an alternate embodiment of the bracelet

FIG. 10 is a front view thereof.

FIG. 11 is a rear view thereof.

FIG. 12 is a side view thereof.

FIG. 13 is a side view thereof.

FIG. 14 is a top view thereof.

FIG. 15 is a bottom view thereof.

FIG. 16 is an exploded view thereof.

FIG. 17 is a perspective view of an alternate embodiment of the bracelet

FIG. 18 is a front view thereof.

FIG. 19 is a rear view thereof.

FIG. 20 is a side view thereof.

FIG. 21 is a side view thereof.

FIG. 22 is a top view thereof.

FIG. 23 is a bottom view thereof.

FIG. 24 is an exploded view thereof.

FIG. 25 is a perspective view of an alternate embodiment of the bracelet

FIG. 26 is a front view thereof.

FIG. 27 is a rear view thereof.

FIG. 28 is a side view thereof.

FIG. 29 is a side view thereof.

FIG. 30 is a top view thereof.

FIG. 31 is a bottom view thereof; and,

FIG. 32 is an exploded view thereof.

The broken lines in FIGS. 8 and 16 depict portions of the bracelet that form no part of the claimed design.

1 Claim, 16 Drawing Sheets
